US0D1053648S

(12) **United States Design Patent** (10) **Patent No.:** **US D1,053,648 S**
(45) **Date of Patent:** **** Dec. 10, 2024**

(54) **TLTING FRAME**

(71) Applicant: **Tiankang Technology Co., Ltd.**,
Jiaxing (CN)

(72) Inventors: **Klaus Bellingroth**, Jiaxing (CN); **Jun Cai**, Jiaxing (CN); **Peng Sun**, Jiaxing (CN); **Peng Liu**, Jiaxing (CN)

(73) Assignee: **Innovative Sleep Technologies**

(**) Term: **15 Years**

(21) Appl. No.: **29/917,549**

(22) Filed: **Nov. 21, 2023**

(30) **Foreign Application Priority Data**

Nov. 10, 2023 (CN) 202330734622.7

(51) **LOC (14) Cl.** **06-06**

(52) **U.S. Cl.**

USPC **D6/718**; D6/392

(58) **Field of Classification Search**

USPC ... D6/367, 368, 382, 383, 392, 718, 718.11;
D24/183, 184

CPC A47C 19/00; A47C 19/12; A47C 19/045;
A47C 19/04; A47C 19/02; A47C 19/021

See application file for complete search history.

(57) **CLAIM**

The ornamental design for a tilting frame, as shown and described.

DESCRIPTION

FIG. 1 is a first perspective view of a tilting frame showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the tilting frame thereof.

The broken lines shown in the drawings depict portions of the tilting frame that form no part of the claimed design.

1 Claim, 9 Drawing Sheets
